CLAIM

The ornamental design for a running board for a vehicle, as shown and described.

DESCRIPTION

FIG. 1 is a perspective view of a running board for a vehicle showing our new design it being understood that the broken lines are for illustrative purposes only and form no part of the claimed design;

FIG. 2 is a greatly enlarged right end elevation view thereof, the left end being a mirror image of that shown; FIG. 3 is a greatly enlarged sectional view thereof taken along line 3—3 in FIG. 4;

FIG. 4 is an enlarged top plan view thereof;

FIG. 5 is an enlarged bottom plan view thereof;

FIG. 6 is an enlarged front elevation view thereof; and,

FIG. 7 is an enlarged rear elevation view thereof.
